UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

METHOD OF FORMING ENVELOP-BLANKS.

1,144,950.

Specification of Letters Patent. Patented June 29, 1915.

Application filed August 11, 1911. Serial No. 643,512.

To all whom it may concern:

Be it known that I, WILLARD E. SWIFT, a citizen of the United States, residing at Worcester, in the county of Worcester and 5 Commonwealth of Massachusetts, have invented a new and useful Improvement in Methods of Forming Envelop-Blanks, of which the following is a specification accompanied by drawings, forming a part of the 10 same.

My invention relates to a method of forming envelop blanks which are to be cut and folded upon that class of envelop machines adapted to manufacture envelops from a 15 continuous web of paper, and it has for its object to enable envelops of different sizes to be made from blanks of uniform length and width.

My present invention is applicable to that 20 class of machines known as rotary envelop machines, in which the continuous strip of paper of uniform width is fed by longitudinal movement through the machine, the entire length of the blanks being determined 25 by a transverse cutting mechanism operating at fixed periods in the operation of the machine. In machines of this class it has been customary to change the transverse cutting mechanism in order that it might operate at 30 more or less frequent intervals as longer or shorter envelops were required. This necessitated a reconstruction of a considerable portion of the machine, and it is the object 35 of my present invention to provide a method of forming blanks from a continuous strip for envelops of varying sizes without changing the length of the blank, enabling the same transverse cutting mechanism to be employed without change in its periods of 40 operation.

My invention is adapted for use in connection with any so called rotary machine which operates upon a continuous strip of paper, or of the class of envelop machines 45 represented by the machine described in the patent issued to James West, July 14, 1908, No. 893,042.

In the accompanying drawings I have 50 illustrated the method of varying the size of the envelop with blanks of uniform length and width.

Figure 1 represents an envelop blank formed from a section of a continuous strip of paper, and illustrating by broken lines 55 my method of varying the size of the body of

the envelop without changing the length of the blank. Figs. 2, 3 and 4 represent three sizes of completed envelops folded from the blanks illustrated in Fig. 1. Fig. 5 represents a portion of a continuous strip showing the method of forming the blanks for envelops of different sizes by the operation of a rotary envelop machine by a change in the length of the envelop. Fig. 6 illustrates the method of varying the size without a 65 change of length, and Figs. 7, 8 and 9 represent folded envelops of different widths.

Similar reference letters refer to similar parts in the different views.

A continuous strip of uniform width, represented in Fig. 5, is moved through the machine in the direction of the arrow *a*. Sections *b*, *c* are removed from its sides by any suitable cutting mechanism, such, for example, as that shown in the aforesaid patent to 70 James West. The reduced portions of the strip are then severed on the broken lines *d*, by a transverse cutting mechanism forming individual blanks, as represented by full lines in Fig. 1, comprising side flaps *e* and *f*, 75 a back flap *g* and a seal flap *h*. One of the side flaps is gummed at *i* and the back flap is gummed at *j*, Fig. 1. The side flaps are then folded on the broken lines *k* and *l* with their edges overlapping, and the back flap 80 *g* is folded on the broken line *m*, forming the body portion of an envelop represented in Fig. 2.

By increasing the length of the sections *b* and *c* which are removed from the sides of 85 the continuous strip, I decrease the length of the side flaps and proportionately increase the aggregate length of the end flaps, thereby reducing the size of the body portion of the folded envelop without changing the 90 position of the transverse cut *d*. For example, if the sections *b* and *c*, Fig. 5, are increased by the additional sections *n* and *o*, the body of the envelop will be reduced in 95 length to that shown in Fig. 3. If the sections *p* and *q* are also removed the body portion of the envelop will be still further reduced to the size shown in Fig. 4. In the 100 reductions named, the length of the seal flap will be correspondingly increased in length, 105 as shown at *r*, Fig. 3, and *s*, Fig. 4. With each variation in the length of the side flaps I prefer to maintain a uniform width of the tip or free end of the seal flaps. As the 110 line of fold of the seal flap is moved farther

from its tip the angle between the line of fold and the side of the seal flap is increased as illustrated in Fig. 1, where the angles between the sides of the seal flaps and their line of fold for each of the three sizes shown are respectively t, u, v ; t, w, x ; and t, y, z , thereby maintaining a uniform width of the tip of the seal flap.

In Fig. 6 the sections removed to form an envelop, as shown in Fig. 7, are indicated by broken lines A. If sections indicated by the broken lines B are removed, the end flaps C are reduced in width, bringing the lines of fold between the body of the envelop and seal flap D and back flap E nearer together, forming an envelop of the size shown in Fig. 8, in which the seal flap D and back flap E are each equally increased in size to correspond with the reduction in the width of the body of the envelop. If sections indicated by the broken lines A on the right hand side and F on the left hand side be removed, the envelop will remain the same width but with the back flaps of the same width as in Fig. 7, while the seal flap only will be increased in width.

In forming each of the sizes of envelops, shown in Figs. 7, 8 and 9, the continuous strip is severed transversely on the dash and dot lines G, making all the blanks of uniform length.

The variation in the sizes of the envelops

is accomplished in the strip shown in Fig. 5 and in the strip shown in Fig. 6, by varying the areas of the sections removed from the sides of the continuous strip, in Fig. 5 they are increased in length, while in Fig. 6 they are increased in both length and width. In both cases the spaces between the transverse cuts by which the strips are severed into individual blanks remain the same making the blanks of uniform length.

I claim,

1. The within described method of forming blanks from a continuous strip, for envelops varying in that dimension running lengthwise of the strip, consisting in varying the areas removed from the edges of the strip, and severing the strip transversely at uniform intervals.

2. The within described method of forming blanks from a continuous strip of uniform width for envelops of different heights, consisting in removing sections of the edges of said strip of different areas, for different heights of envelops required, and severing the strip transversely at its reduced portions at uniform intervals.

Dated this eighth day of August 1911.

WILLARD E. SWIFT.
